US0D1016938S

(12) **United States Design Patent** (10) **Patent No.:** **US D1,016,938 S**
(45) **Date of Patent:** **** Mar. 5, 2024**

(54) **ADJUSTABLE KETTLEBELL HANDLE SYSTEM**

(71) Applicant: **QIDUO E-COMMERCE (ZHEJIANG) CO., LTD.**, Ningbo (CN)

(72) Inventor: **Guangchao Liu**, Hengyang (CN)

(73) Assignee: **QIDUO E-COMMERCE (ZHEJIANG) CO., LTD.**, Ningbo (CN)

(**) Term: **15 Years**

(21) Appl. No.: **29/839,230**

(22) Filed: **May 19, 2022**

(51) **LOC (14) Cl. 21-02**

(52) **U.S. Cl.**

(57) **CLAIM**

The ornamental design for an adjustable kettlebell handle system, as shown and described.

DESCRIPTION

FIG. 1 is a perspective view of an adjustable kettlebell handle system, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

1 Claim, 7 Drawing Sheets
